CHANGEABLE NEON SIGN

Filed Aug. 24, 1933

UNITED STATES PATENT OFFICE

1,991,099

CHANGEABLE NEON SIGN

Herman S. Katz, Cincinnati, Ohio, assignor to
 Samuel Levites and Isadore Nathan, both of
 Cincinnati, Ohio

Application August 24, 1933, Serial No. 686,566

9 Claims. (Cl. 40—130)

My invention relates to means for detachably and interchangeably supporting neon tubing in operative position.

Heretofore neon signs have been so constructed that the glass tubing comprising the wording and positive and negative electrodes have been permanently attached to the sign or casing, the electrodes being inserted in housings in the casing and the tubing attached by means of a wire cord which was then made fast to the casing. When new wording was desired it was necessary to dismantle the entire sign; that is, it was necessary to open the sign, the wires supporting the tubing would have to be removed, new holes would have to be put in the sign and the housings holding the electrodes re-positioned to accommodate the new wording; it would then also have to be wired as in the first instance.

The object of my invention is to provide simple, efficient, convenient, durable and inexpensive means whereby the positive and negative electrodes of a neon tubing may be readily inserted in a sign cabinet in an operative position, or as readily removed therefrom, for the purpose of substituting a neon tubing of different wording or modified form.

In the drawing which serves to illustrate a preferred embodiment of my invention:

Fig. 1 is an isometric view of a sign cabinet having my invention applied thereto;

Fig. 2 is an inverted plan view of the cabinet with the bottom cover removed;

Fig. 3 is a sectional view on line 3—3 of Fig. 2; and

Fig. 4 is an isometric view of a rubber diaphragm embodying my invention.

In the embodiment of my invention as illustrated and which shows a preferred construction I provide a disc 1 preferably of rubber or other suitable resilient or elastic material having intersecting slits 2 converging at the center and extending outwardly therefrom in the manner of spokes as illustrated in Fig. 4 and forming a plurality of converging elastic tongues. This disc 1 is positioned as a diaphragm in the openings 3 preferably placed at the ends of the cabinet 4 on its face 5. Extending inwardly and mounted on the inner side of the face 5 are porcelain housings 6 and 7 adapted to receive positive and negative electrodes 8 and 9, respectively, of tubing 10 when said electrodes are inserted in the openings 3 in the face of the cabinet. The electrodes 8 and 9 form the ends of the neon tubing or wording 10 and are

adapted to contact the electrical posts 11 and 12 whereby electrical energy is transmitted to the rare gases in said neon tubing 10, through conductors 13 and transformer 14.

A saucer-shaped protective metal cap 15 having an opening 16 is mounted over the openings 3 in face 5. Circular rings of mica 17 and 18 are interposed between the face 5, disc 1, and housings 6 and 7, respectively. Bolts 19 and 19' together with nuts 20 and 20' are the means of fastening the housing, protective cap, elastic rubber disc and mica insulators to the cabinet. Similar housings 23 and 24 may be mounted directly beneath openings in the top of the sign cabinet, being identical in construction to that described, and as shown in Fig. 3.

The cabinet 4 is so built that its face 5 is at an acute angle to the base 21 and at an obtuse angle to the top 22. The cabinet may be set upon its base on a stand, the angle of the front face to the base being such that the wording may be observed without the effort of the observer looking down upon it; or the cabinet may be suspended by chains 25 in which case it is so balanced that the face is absolutely straight in a perpendicular plane to the ground thereby giving perfect horizontal vision. It is to be understood that any number of these openings together with rubber discs and housings may be applied to a cabinet the size of the cabinet governing the number accordingly.

It can readily be seen, when the electrodes are inserted through the openings 3, they will be securely but removably held by the converging elastic tongues of the rubber discs 1, thereby eliminating the use of any other fastening means, such as wires, to hold the tubing in proper position. In this manner tubing of different wording may be readily and easily substituted when a change is desired.

My invention is capable of considerable modification without departure from its scope or spirit as defined in the claims.

What I claim as new and desire to secure by Letters Patent is:

1. In a changeable neon sign, a cabinet provided with electrical connections on its interior and having a pair of openings therein, a flexible member provided with intersecting slits forming reversible converging elastic teeth mounted in each of said openings and adapted to detachably receive the ends of a neon sign tube and yieldably support said tube.

2. In a changeable neon sign, a cabinet provided with electrical connections therein, open-

ings in said cabinet, a non-conducting resilient support mounted in each opening and provided with a plurality of converging elastic teeth, in combination with a neon tube detachably and 5 adjustably mounted in each opening, said teeth yieldably but firmly engaging said tubes and said teeth projecting inwardly in contact with the tube when it is being inserted and reversing their position and projecting outwardly when 10 said tube is being removed.

3. In a changeable neon sign, a cabinet provided with an opening, a housing mounted in said cabinet opposite said opening, an elastic non-conducting member attached to said housing and cabinet and having an orifice provided with converging elastic reversible teeth adapted to detachably receive and yieldably support a neon sign tube.

4. In a changeable neon sign, a cabinet provided with an opening, a housing mounted in said cabinet opposite said opening, mica rings and an elastic non-conducting member interposed between said mica rings, said mica rings and elastic non-conducting member being secured between said housing and said opening.

5. In a changeable neon sign, a cabinet provided with an opening, a housing mounted in said cabinet opposite said opening, mica rings and an elastic non-conducting member interposed between said mica rings, said mica rings and elastic non-conducting member being secured between said housing and said opening, and a protecting cap having an opening therein mounted on the outer side of said cabinet opposite said housing.

6. In a changeable neon sign, a cabinet provided with electrical connections therein, an opening in said cabinet, a housing secured within said cabinet opposite said opening and having a spring electrical contact member in its inner end connected to one of said electrical connections, an elastic rubber disc mounted in said opening and having a plurality of intersecting slits forming elastic converging teeth, and a mica ring interposed between said disc, housing and cabinet respectively.

7. In a changeable neon sign, a cabinet, electrical connections therein, a housing attached to said cabinet and to one of said electrical connections and having a spring electrical contact therein, said cabinet having an opening opposite said housing and having a non-conducting elastic disc provided with a plurality of supporting converging co-operating tongues, in combination with a detachable neon sign tube having an end projecting through said disc into engagement with said spring electrical contact and out of engagement with said housing and yieldably supported therein by said tongues.

8. In a changeable neon sign, a cabinet having an opening therein, a housing disposed in said cabinet opposite said opening, an electrical connection mounted in said housing and having a contact on its interior, a rubber disc mounted across said opening and having a plurality of intersecting slits whereby a plurality of converging elastic teeth are formed, a mica ring interposed between said housing and cabinet on each side of said rubber disc, a protective cap having an opening therein mounted adjacent said first-named opening and means for securing said parts together, in combination with a neon tube terminal detachably extending into said housing in spaced-apart relation therefrom to form engagement with said electrical connection and be supported out of contact with said housing by said yieldable teeth, which teeth are reversible when said terminal is withdrawn for the purpose of replacing it with a new tube or substituting another sign in place thereof.

9. In a changeable neon sign, a cabinet having a base, face and top, said face being at an acute angle to the base and said top in a plane out of parallel with the base, said face being provided with a pair of openings and a flexible nonconducting member mounted in each of said openings provided with intersecting slits forming elastic reversible teeth adapted to detachably receive and yieldably support a removable neon sign tube.
